EMILE J. BEIN, OF NEWARK, NEW JERSEY.

SURFACING-MACHINE.

981,159.

Specification of Letters Patent. Patented Jan. 10, 1911.

Application filed February 3, 1910. Serial No. 541,678.

To all whom it may concern:

Be it known that I, EMILE J. BEIN, a citizen of the United States, residing at Newark, in the county of Essex and State of New Jersey, have invented certain new and useful Improvements in Surfacing-Machines; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to a surfacing machine and more particularly to one in which an abrasive belt is employed, usually a sand-paper belt.

The machine embodies pulleys on which 20 the belt is adapted to travel, these pulleys being mounted on the end of a beam which is adapted to rock.

The machine is preferably made with a beam on each side of a standard, which 25 standard supports the beams and also the driving shaft, the driving shaft having a pulley mounted in the center of the standard and the beams having means co-acting with the standard for holding the beams in 30 adjusted positions.

The machine is adapted for use as a horizontal or a vertical machine, or it can be used at any angle intermediate of the vertical and the horizontal, the beam being 35 provided with a table on which the work can be held or supported when it is being ground by means of the abrasive belt.

The invention also provides a driving belt which drives the abrasive belt by means 40 of a power belt which runs over the driving pulley and also over one of the pulleys on which the belt runs, engaging the latter and also the abrasive belt, whereby all the elements work in unison.

45 The invention is further designed to provide platens which are removably arranged on the beam so that the machine can either be used as a cushion or with the platen, according to the work to be done.

50 The invention is illustrated in the accompanying drawing, in which—

Figure 1 is a perspective view of the machine, one of the beams being shown arranged vertically and the other arranged horizontally. Fig. 2 is a side view of the machine 55 partly broken away showing one of the

beams in its vertical position. Fig. 3 is a cross-section of one of the beams and showing the standard and the driving mechanism in elevation, the duplicate apparatus on the opposite side of the standard being left off.

The device comprises a standard or support having a base 10 and an upright portion 11 which is forked at its top, as at 12, to form the bearings 13 between which is 60 mounted the power pulley 14. The power pulley operates the driving shaft 15 which can extend only from one side of the standard, but preferably extends on both sides, and is provided on both its ends with a surfacing apparatus, and since these are in 65 duplicate, one will be described in particular. A beam 16 is arranged to rock in relation to the standard, swinging to either a horizontal or a vertical position and having 70 a curved bar 17 which has a slot 18 through which can be placed a bolt 19 which screws into the standard 11 and can lock the beam in its adjusted positions, when the beam is tipped beyond the vertical by a 75 removable socket wrench 20 shown in Fig. 3 in dotted outline. When the beam is moved to a vertical position, or a position between the vertical and horizontal, the bolt 19 is removed and a screw 18^a, secured to a bracket 80 18^b on the standard and passing through the slot 18, holds the beam and its accessories steady. On each end of the beam is a bearing 21, these bearings both being adapted to 85 slide on the beam and being in engagement with a screw 22 which fits into a lug 23 and is provided with a hand-wheel 24. By means of the screws 22 the bearings 21 are 90 adjusted toward and from each other. Each bearing is provided with a shaft 25 on which 95 is fastened a belt pulley 26. Over these two pulleys 26 runs an abrasive belt 27 which is used for surfacing article and is kept taut by the adjustment of the pulleys toward and from each other.

Intermediate of the pulleys 26, and preferably at the pivot on the drive shaft 15, is a driving pulley 28 and a drive belt 29 passes over the pulley 28 and also over one of the pulleys 26, passing between the pulley 26 and the belt 27, thus acting to drive one of the pulleys 26 and insuring the movement of the belt 27. The drive belt 29 also has another function, and that is to act as a cushion when an article to be surfaced or 105 finished is placed against the abrasive belt. For certain kinds of work this is necessary,

and the drive pulley operating at the same speed as the abrasive belt causes no undue friction between the belt and its backing, and at the same time permits enough give or resiliency to the belt to suit certain kinds of work.

Fastened by suitable brackets 30 is a bar 31 which is adapted to hold, near either of its ends and between either of the pulleys 10 26 and the drive pulley 28, a table 32. Each table is adapted to bear up close against the back of the abrasive belt and is adapted to be held in place by suitable hand screws 33. At each end of the bar 31 is an offset portion 15 34 against which is adapted to rest a slide 35, this slide being provided with a slot 36 which slides on a screw 37, which screw passes into the bar 31 and holds the slide in its adjusted positions. On the end of the 20 slide is a bearing 38 into which fits a bolt 39 which in turn is provided with a nut 40, in the shape of a hand wheel, which acts to tighten up the bolt 39, when necessary, which forces one of the brackets 41 of the 25 table against the bearing 38 and thus holds the table 42 at any position it is adjusted to.

This machine is adapted for a great many uses and, having the platen and also the cushion backing for the abrasive belt, permits of a great variety of work when it is tilted partly, for instance when at an angle of about forty-five degrees the under side of each of the pulleys, or the belt passing over the pulley, can be used as a buffering wheel. The table 42 can be arranged at an angle to the abrasive belt so that when the beam and the pulleys, with the abrasive belt, are arranged at an angle out of the vertical, the table can be made to set horizontal so that in any angular grinding the work can be fed level or horizontal and the belt is inclined.

Having thus described my invention, what I claim is:—

45 1. A surfacing machine comprising a standard, a beam on the standard, pulleys arranged on the ends of the beam, a pivotal connection for the beam and the standard arranged between the pulleys, an abrasive belt passing over the pulleys, a drive pulley between the first mentioned pulleys, means for adjusting the first mentioned pulleys toward and from each other and a power belt passing over the driving pulley and over 50 one of the belt pulleys and passing between the abrasive belt and the last mentioned pulley and also being adapted to act as a cushion for the abrasive belt.

60 2. A surfacing machine comprising a standard, a beam supported substantially equi-distant between its ends on the standard, a driving shaft passing through the beam and through the standard on the pivot of the beam, belt pulleys arranged to rotate 65 on the ends of the beam, means for adjust-

ing the belt pulleys toward and from each other, a driving pulley on the shaft, an abrasive belt passing over the belt pulleys, and a driving belt passing over the driving pulley and over one of the belt pulleys and 70 between the latter and the abrasive belt.

3. A surfacing machine comprising a standard, a beam supported substantially equi-distant between its ends on the standard, a driving shaft passing through the beam and through the standard on the pivot of the beam, belt pulleys arranged to rotate 75 on the ends of the beam, means for adjusting the belt pulleys toward and from each other, a driving pulley on the shaft, an abrasive belt passing over the belt pulleys, a driving belt passing over the driving pulley and over one of the belt pulleys and 80 between the latter and the abrasive belt, and co-acting means between 85 the beam and the standard for adjustably securing the beam in its tilted positions.

4. A surfacing machine comprising a standard, a beam supported substantially equi-distant between its ends on the standard, a driving shaft passing through the beam and through the standard on the pivot of the beam, belt pulleys arranged to rotate on the ends of the beam, means for adjusting the belt pulleys toward and from each 90 other, a driving pulley on the shaft, an abrasive belt passing over the belt pulleys, a driving belt passing over the driving pulley and over one of the belt pulleys and 95 between the latter and the abrasive belt, a curved 100 bar on the beam, the curved bar having a slot therein concentric with the pivot of the beam, and means engaging the curved bar and passing through its slot into the standard for adjustably securing the beam in its 105 tilted positions.

5. A surfacing machine comprising a standard, a beam arranged in swinging relation on the standard, a shaft passing through the standard and the beam at the 110 point where the beam swings, belt pulleys arranged on the ends of the beam, means for adjusting the pulleys toward and from each other, a driving pulley on the shaft, an abrasive belt on the belt pulleys, a driving 115 belt passing over the driving pulley and over one of the belt pulleys between the latter and the abrasive belt, a table secured to and adapted to swing with the beam, and means for securing the table in different 120 angular positions to the abrasive belt.

6. A surfacing machine comprising a standard, a beam adapted to swing on the standard intermediate of the ends of the beam, a shaft passing through the standard and the beam at the point where the beam swings, a power pulley on the shaft, a bar secured to the beam, belt pulleys arranged on the ends of the beam, a driving pulley arranged on the shaft and between the belt 130

- pulleys, an abrasive belt passing over the belt pulleys, a belt passing over the driving pulley and adapted to drive one of the belt pulleys, platens, means for detachably securing the platens between either of the belt pulleys and the driving pulley, a table secured to the beam, and means for adjustably securing the beam on the standard in its different tilted positions.
- 10 7. A surfacing machine comprising a standard, a beam pivotally supported approximately at its center on the standard, belt pulleys arranged on the end of the beam, an abrasive belt passing over the belt pulleys, a driving pulley between the belt pulleys, means for adjusting each belt pulley toward and from the driving pulley, means for securing the beam to the standard in its tilted positions, and a belt passing over the driving pulley and one of the belt pulleys for rotating the belt pulleys and the abrasive belt.
- 20 8. A surfacing machine comprising a standard, a beam pivoted approximately at its center on the standard and arranged to swing vertically thereon, pulleys arranged on the ends of the beam, a driving shaft passing through the beam and through the standard on the pivot of the beam, an abrasive belt passing over the pulleys, means for adjustably securing the beam to the standard in its tilted positions, and means for driving the pulleys and the belt from the driving shaft.
- 25 9. A surfacing machine comprising a standard, a beam pivoted approximately at its center to the standard and arranged to swing thereon, belt pulleys on the ends of the beam, an abrasive belt passing over the pulleys, means for adjusting the belt pulleys toward and from each other, a driving pulley between the belt pulleys, a driving belt passing over the driving pulley and over one of the belt pulleys, a curved slotted bar on the beam, the curved bar being connected at its ends to the beam on opposite sides of the pivotal point of the beam, a pin on the standard passing through the curved slot in the bar, and means on the pin for engaging the bar for securing the beam in its tilted positions.

In testimony, that I claim the foregoing, I have hereunto set my hand this 1st day of February 1910.
